(57) **CLAIM**

We claim, the ornamental design for signage in a building environment, as shown and described.

DESCRIPTION

FIG. 1 is a perspective view of signage in a building environment, showing our new design;
FIG. 2 is a side view thereof;

FIG. 3 is another side view thereof;

FIG. 4 is a front view thereof;

FIG. 5 is a rear view thereof;

FIG. 6 is a top view thereof;

FIG. 7 is a bottom view thereof;

FIG. 8 is an exploded perspective view thereof; and,

FIG. 9 is another exploded perspective view thereof.
The broken lines depict portions of the signage that form no part of the claimed design.**1 Claim, 6 Drawing Sheets**FIG. 1

FIG. 2
